UNITED STATES PATENT OFFICE.

ORVILLE C. MANN, OF OAK PARK, ILLINOIS.

RAILWAY-GRADER.

1,101,030.

Specification of Letters Patent. Patented June 23, 1914.

Application filed April 6, 1910. Serial No. 553,792.

To all whom it may concern:

Be it known that I, ORVILLE C. MANN, a citizen of the United States, residing at Oak Park, in the county of Cook and State of

Illinois, have invented new and useful Improvements in Railway-Graders, of which the following is a specification, reference being had to the accompanying drawings, forming a part thereof.

10 The purpose of this invention is to provide an improved construction for performing certain parts of the work of grading a railway road bed, particularly distributing and leveling the earth and shaping the top and sides of embankments and sides of cuts.

15 It consists in the elements and features of construction shown and described as indicated in the claims.

In the drawings: Figure 1 is a side elevation 20 of the forward portion of a car structure equipped with this invention, showing the earth-deflecting devices in position out of service. Fig. 2 is a similar view showing the distributing devices in operative position. Fig. 3 is a plan view of the part shown in Figs. 1 and 2 in substantially the position in which they appear in Fig. 2, the bed of the car being broken away in parts to show portions of the structure underneath 30 the same. Fig. 4 is a section at the line 4—4 on Fig. 3. Fig. 5 is a section at the line 5—5 on Fig. 2. Fig. 6 is a section at the line 6—6 on Fig. 2. Fig. 7 is a section at the line 7—7 on Fig. 5. Fig. 8 is a detail side elevation of a part of one of the wings showing a plow attaching device thereon. Fig. 9 is a plan view of the structure shown in Fig. 8. Fig. 10 is a detail side elevation of the plow and its attachment. Fig. 11 is a detail section at the line 11—11 on Fig. 10. Fig. 12 is a perspective view of the adjustable member of a post provided for carrying the pivot of the deflector to the car. Fig. 13 is a detail side elevation of the deflector having a supplemental member for bank-shaping attached thereto. Fig. 14 is a plan view of the structure shown in Fig. 13. Fig. 15 is a side elevation of a portion of the car having the main deflector as shown in Figs. 1, 2 and 3, and having a bank shaper attached thereto. Fig. 16 is a plan view of the rear end portion of the car and deflecting devices thereon at one side for shaping embankment, said devices being

shown at operative position. Fig. 17 is a side elevation of the structure shown in Fig. 16. Fig. 18 is a side elevation of the same with the bank-shaping devices out of operative position. Fig. 19 is a plan view of the rear end portion of the car, having similar deflecting devices at the other side from those shown in Figs. 16, 17 and 18, with apertures especially adapted and adjusted for shaping the side of a cut or embankment alongside the track and higher than the same, said devices being shown in operative position. Fig. 20 is a side elevation of the structure shown in Fig. 19 at the same position. Fig. 21 is a section at the line 21—21 on Fig. 16. Fig. 22 is a detail side elevation of a portion of the deflecting and bank-shaping device shown in Fig. 17, having the supplemental bank-shaping device secured out of operative position with respect to the deflector. Fig. 23 is a detail section at the line 23—23 on Fig. 16. Fig. 24 is a perspective view of the pivot block and pivot therein, shown in Fig. 23. Fig. 25 is a detail view at the line 25—25 on Fig. 22. Fig. 26 is a detail section at the line 26—26 on Fig. 2.

The structure shown in the drawings consists of flat car X, on which are mounted deflectors and earth-distributing and bank-shaping devices for performing the various parts of the work of earth-distributing, pertaining to grading and shaping the road bed of railways. These devices comprise the following, which will be described in their order: First. Main deflectors or distributors in the nature of spreaders or gatherers which are hinged at their forward ends to the forward part of the car and constructed for swinging outward divergently from the car to engage, distribute and level material which may be positioned along the sides of the track; these devices are adapted to operate either for gathering inward or spreading outward, according to the direction of travel of the car; but in general since the greater use is for distributing outward, the end of the car which moves forward for that purpose, is commonly referred to in this specification as the front end of the car. Second. Deflectors which are positioned under the forward part of the car for spreading out and also, for gathering inward material from between or to be deposited be-

tween the rails. Third. Attachments for mounting plows on the main deflectors and plows adapted for being so mounted to plow or loosen up the earth at the side of the 5 track and for cleaning out and shaping the drain ditch at the side. Fourth. Devices preferably mounted at opposite sides of the rear end or end opposite that under which the interior spreading and the gathering de- 10 vices are mounted, particularly designed for shaping and trimming up an embankment of an upraised road bed, and for trimming the sides of a cut or side of an embankment extending alongside and higher than the 15 track.

All these devices may be employed on the same piece of work sometimes in conjunction and sometimes successively, one part preparing the way for another to follow it.

20 In addition to the working devices above described, the car contains the operating apparatus for manipulating the different devices in adjusting them to the various positions suitable for the various parts of the 25 work and to the different character of the performance required by different situations.

The main deflectors and their operating and controlling connections will be first de- 30 scribed. The drawings are made to show only these devices at one side of the car; but it may be understood that the car is similarly equipped on both sides and that the devices applied similarly on the other side not 35 shown. Each of these deflectors comprises a main wing, 1, whose operating position for distributing material along the track, is extended at an angle of about 30° or 40° back obliquely outward from the track with 40 the lower and inner edge about level with the ties, or slightly higher or lower; accord- 45 ing to the conditions, and extending thence outward usually with a slight downward slope, or as may be desired, the lower edge being shaped to any desired contour of the 50 road bed, being shown straight in the draw- 55 ings. The deflector comprises, in addition to this main wing, a heel member, 2, which requires greater height than is necessary for 60 the wing, 1, because its function is to attack a pile or ridge of sand or gravel, which may extend along the track, having been dumped usually from cars on the track, and therefore near thereto, which pile or ridge be- 65 comes lower as it is spread outward into the path of the main wing. The heel member, 2, laps in front of the main wing, 1, so that it delivers the material which it engages, outward in front of the main wing, and also 70 so that it is itself propelled by the engage- 75 ment behind it of the main wing.

The entire deflector comprising the parts, 1 and 2, must be connected so as to fold up close to the car for passing through narrow 80 cuts and bridges, and for being carried com-

pactly when out of service. When thus folded up all parts must come within a pre- 85 scribed vertical compass for passing under viaducts, tunnels, etc., these requirements involving both swinging the members of the 90 deflector inward, and also moving them up- 95 ward; and inasmuch as the heel member, 2, is higher—that is greater in vertical di- 100 mension,—than the main wing, it will be evident that if the pivotal point for upward 105 swinging of the entire deflector, comprising 110 both these members, were to be fixed at the forward inner edge or end of the heel mem- 115 ber it would have to be at the extreme up- 120 per forward corner of that member, since otherwise the upward swinging could not be concurrent with the inward swinging, be- 125 cause any portion of the heel member above the pivot would swing inward and down- 130 ward in the upward movement of the hold- ing device, and would therefore have to be low enough to pass under the car, which would make it too low for efficiency. For this reason the heel member is preferably mounted for swinging horizontally only, its up-and-down movement being a sliding movement and the main wing is pivoted for both its movements at a point in its width and in the height of the car such that the upper forward corner 95 is readily accommodated in the short dis- 100 tance to which the pivot is offset from the side of the car. Since for different situations it is desirable to adjust the entire de- 105 vice for operating at different heights, the pivot of the main wing is mounted for ver- 110 tical adjustment with respect to the car, and the main wing and heel member are further connected so that the heel member is raised and lowered by the raising and lowering of 105 the pivotal support of the main wing. For these various purposes the construction shown, comprises, what may be called a hol- 115 low post, mounted on the side of the car, comprising two channel bars, 3, 3, mounted 120 with their channels facing each other, so as to furnish a vertical slide bearing for a slid- 125 ing post, 4, (see Fig. 12) in which near the lower end, the pivot fitting, 5, for the main wing, 1, is secured. For adjusting and se- 130 curing the post member, 4, at different heights with respect to the car, and in the hollow post, 3, 3, there is provided a spring latch, 6, fastened onto the side of the hollow post, and adapted to engage any one of the holes, 4^a, in the post member, 4, said latch reaching said holes through a hole, 3^a, in the web of the rear member of the channel bar post, 3, 3. For raising and lowering the post member, 4, it is connected to the end of a cable, 7, which passes over an elevated guide pulley, 8, on the channel bar post, 3, 3, and thence down around a pulley, 9, mounted upon the upper end of the stem of a piston, 10, operating in cylinder, 11, the

cable passing from said pulley to a point of fastening on the frame structure of the car. The posts, 3, are provided with a scale, 3^a, graduated in inches and an index finger, 4^a, is attached to the post, 4, for reading the height of adjustment of the adjustable post.

Compressed air or other motive fluid is supplied to the cylinder, 11, for operating the piston therein to retract downward the pulley, 9, to lift the post member, 4. The latch, 6, is connected to an operating cord, 13, extending to a point where it may be manipulated by the operator to withdraw the latch when a motive fluid is admitted to the cylinder, 11. The heel member, 2, is mounted on a vertical pivot rod, 14, secured to and offset from the forward side of the hollow channel bar post, 3, said heel member having two bearing lugs, 15, 15, by which it is pivoted on said vertical pivot rod, the said bearing lugs being much nearer together than the length of the rod, so that said heel member can slide vertically on a rod for a considerable distance sufficient to accommodate all desirable changes of elevation of the heel member, both in its operation and in the movements involved in folding the device up out of service. As stated, the heel member laps outside the forward end of the main wing, 1. It is connected to said main wing for partaking of the inward and outward swinging movement of the main wing, and for raising and lowering in the upward swinging movement of the main wing hereinafter described, and also in its vertical adjustment by means of the cable as above described, by an abutment, 16, projecting from the upper rear corner of the heel member overhanging the upper edge of the wing, having a roller for riding upon said upper edge, and its inner end projecting down behind the edge of the wing. By this construction, it will be observed that the heel member, at the position of the device out of service, as shown in Fig. 1, is elevated so as to clear the track by a considerable distance, and that as by the outward and downward swinging of the wing, 1, the forward end of said heel member is swung inward, it is also lowered so as to permit that end to swing in under the car and stand, if desired, close to the rail at the working position of the device. This forward portion of the heel member, which is to extend under the car, is reduced in height, as seen clearly in Fig. 1, and it is also preferably provided with an angle recess, 2^a, at the lower forward corner for overhanging the rail, to clean the rails on top as well as the outer side.

On the forward side of the post, 3, there is pivoted a depending latch bar, 90, which has at its lower end an outwardly offset finger, 90^a, (see Fig. 26) extending past the pivot rod, 14, behind the same in position to

engage above the eye, 15, at the lowest ordinary working position of the wing, 1, and heel member, 2, for locking said parts down at said working position. A spring, 90^b, attached to the latch bar reacting against the post, 3, holds the latch finger forward against the pivot rod,—that is, in its operative position. For releasing the latch bar when the latch, 6, is disengaged, a link, 91, is connected to the latch, 6, by its angular bent end, 91^b, extends past the post, 3, and has a finger, 91^a, jutting outward at the forward side of said latch bar, 90, in position to engage the latter and pull it back from the pivot rod, 14, and from above the eye, 15, when the latch, 6, is disengaged.

For holding the heel member, 2, up at a position somewhat higher than it is normally lifted by the action of folding up the wing, 1, out of operative position, as is sometimes desirable, a chain, 2^c, is attached to the post, having a hook, 2^d, at its lower end for engaging an eye, 2^e, at the upper end of the wing.

For permitting the movement of the main wing, 1, so that it will swing outward and be positioned close alongside the car when swung upward out of service, and for causing said wing to be substantially vertical at all operative positions, it is necessarily pivoted so as to swing both vertically and horizontally, and for that purpose the pivotal support, 5, is made in the form of a T, whose stem, 5^a, is journaled in the sliding post member, 4, horizontally and transversely to the length of the car or direction of the track, the wing being pivoted on the vertical cross member of the T for its horizontal swinging. In order to definitely mount and secure the pivot, 5, in the post member, 4, the stem, 5^a, of the pivot is provided with an annular groove, 5^b, and a key pocket is formed in the post transverse to the bearing of the stem, 5^a, therein, in position so that a key, 5^c, inserted in said pocket engages the groove, 5^b, and thereby retains the pivot in the post free to turn about the stem.

For controlling the swinging movement of the wing, as described, its connection to the car comprises, besides the forward pivotal connection above described, links which are pivoted to the wing at the side of the car and which, for holding the wing in vertical position without reliance merely upon the pivot, 5, for that purpose, are connected to the wing at different positions in the width thereof; and in order that with such connection to the wing they may permit the wing to maintain its position in a vertical plane for the entire path of the swinging movement, the links are also similarly spread at their ends, pivoted to the car. For merely controlling the movement of the wing as described, two links, positioned remotely from the rearward pivot would

suffice, and any two of the links shown and connected as described, may be considered the primary controlling links; but in order to thoroughly brace the wings in all parts of its length for the work which it is to perform, it is preferable to provide such links distributed along the length, and the links thus constitute two sets, an upper set, 17, and a lower set, 18. The pivots of the two sets on the car are preferably provided on hangers, or brackets, 19, which depend from the side of the car frame, as seen in Fig. 1. If for the purpose of the work to be done, the forward end of the wing required no vertical adjustment, but could always remain at the same position, that is if the pivot, 5, were not to be vertically moved, the simplest arrangement and positioning of the two sets of links with their pivots on the car, would be with their pivots on the wing in lines converging to the pivot, 5, and with such construction the connections of the links to the car and to the wing might be unaccommodating hinges, that is, joints adapted to fold only in one plane like a door hinge; but in view of the necessity for providing vertical adjustment of the wing at the forward end in order to enable it to reach different levels on the road bed, to perform its work under the varying conditions required to be met, it is necessary to locate the two lines at which the two sets of links are pivoted on the car and on the wing, so that if extended they could not meet unless considerably forward of the pivot, 5, and the practical range of vertical adjustment of said pivot is not more than the distance between said two lines at the point where said lines extend past said pivot. For the best distribution of the bracing which the links afford to the wing, the two pivotal lines at which the upper and lower set respectively are connected, are preferably approximately parallel, both on the wing and on the side of the car. When the two pivotal lines are not positioned converging to the forward pivot of the wing, but are made as above indicated with provision for raising and lowering the said forward pivot, it is necessary to construct the pivotal connections of the links, both to the car and to the wing in a manner which will accommodate a certain amount of fore and aft movement or lateral swinging of the links out of the planes in which any one of them would swing in the raising and lowering movement of the wing if the others were absent. For this purpose it is sufficient to construct the pivotal joints loosely, so that their main movements will be at right angles to the pivot pins with sufficient freedom to allow lateral deflection required, and the amount of play required for accommodation is reduced to the minimum by positioning the several pivots obliquely on the wing and on the car as shown.

In addition to the two sets of links whose pivots are in two lines as indicated on the car and on the wing, there may with advantage be provided an additional brace link, 21, toward the forward part of the wing, but back of the forward pivot. The pivots of such link on the wing and car respectively being located intermediate the two lines at which the links, 17 and 18, are pivoted to the wing, its pivot on the car may be substantially in line with the pivots of the lower sets of links, 20, so that the link is approximately in a horizontal plane when the wing is swung down so the other links trend obliquely downward. It is then adapted to moderately brace the wing against inward pressure when it is operating at such lower position. The need for this additional brace link arises from the fact that the lateral accommodation which would be necessary at the pivots of links having their pivots in line with those of the two sets of links, 17 and 18, increases rapidly as the position of such links nears the forward ends of the wing when the two pivotal lines are not converged to the forward pivot and the provision of a single brace link at intermediate position, and approximately in a line extending from the forward to the rear pivot avoids this difficulty.

In order to vary the oblique angle at which the wing extends off from the car at operative position, the links, 17, 18 and 21, are made extensible, being for that purpose each formed of two pipe members, telescoping one within the other, the outer of the two members having a plurality of holes, 20^a, at any one of which a pin, 20^b, may be inserted to engage a hole in the inner member. The holes, 20^a, on the several links are spaced respectively, so that the proper relative extension of all the links will be made when the pins are engaged in the corresponding holes in the several links.

The resistance of the work to the wing when it is swung down to operative position, if it is either above or below the position at which the links, 17 and 18 are horizontal, tends to crowd it up or down; and it is necessary therefore to provide means for limiting the swing of the wing at the position to which it is adjusted. For locking it at operative position, there is provided an extensible latch bar, comprising telescoped members, 23 and 24, the outer member, 23, being pivoted at an elevated point on the car, preferably at the upper end of the post, 3, 3, the inner member, 24, being engaged for sliding through an eye or staple, 24^a, on the wing near the outer end thereof at its lower side, and having near its outer end an annular groove, 24^b, back of a terminal head, 24^c, the groove being adapted to engage by gravity in the lower side of the eye, 24^a. The two members are 130

connected together adjustably as to their extension, by a pin, 23^a, inserted in any one of a plurality of holes, 23^b, in the member, 23, and engaging the inner member. The members, 23 and 24, will be extended so as to position the groove, 24^b, for engaging the eye, 24^a, when the wing is swung down to desired position for work; the latch being lengthened for holding the wing at a lower position and shortened for holding it at a higher position. For raising and lowering the wing, it is attached to a cable, 25, extending over an elevated guide pulley, 26, on the car, thence down around a lower guide pulley, 27, and thence around a pulley, 28, on the stem of a piston not shown, traveling in a cylinder, 29, as may be readily understood without detail illustration, so that the retraction of the piston in the cylinder by any motive fluid for which connection is provided by way of the pipe, 31, will draw up the cable and lift the wing. In order that the latch may be disengaged automatically, that is, without special attention of the operator when the wing is to be lifted, the cable, 25, is looped under a guide eye, 32, on the upper edge of the wing between its fastening at 33, to the wing, and said guide, and at the looped portion extends through an eye, 34, on the end of a rod, 34, which extends along the upper edge of the wing and at its outer end is connected to a lever, 35, pivoted on the wing, and having an abutment, 35^a, extending under the latch bar, 24, so that it lifts the latch bar when the rod, 34, is pulled inward by the pull on the cable, 25, so that the first effect of such pull is to release the latch before the wing experiences the lifting action of the cable.

The wing above described, mounted and hung as described is adapted for gathering material inward toward the rails when the car runs in the opposite direction from that assumed in the foregoing description. For filling in between the rails either by means of material which has been gathered in toward the rail by the wing, 1, or which has been dumped outside the rails comparatively near thereto, deflectors, 40, are provided under the car, pivoted at the inner end to a support mounted on the car, and adapted to be adjusted for extending obliquely outward across the two rails respectively, and to a position to which their ends are far enough outside the rails to coöperate with the outside wing, 1, to take the material gathered by that wing and deflect it inward across the rail, so that it will be deposited inside the track. For affording pivotal support for the inner ends of these deflectors, 40, a bracket, 41, is mounted upon the underside of the car projecting downward toward the road bed on which pivotal rods, 41^a, are provided, and the deflectors, 40, are pivoted to said rods by eyes, 40^a, so positioned in

the width of the deflectors with reference to the length of the pivot rods that the deflectors may be raised or lowered on the pivot rod, being stopped at the lowest position by the encounter of the eye with the bearing of the rod. For raising and lowering the deflectors and for securing them at adjusted position, a vertically reciprocating stem, 42, mounted in a vertical pivot bearing, 43, on the car, has a cross bar, 44, at its lower end, which extends across the upper ends of the two deflectors; and is connected to them by a headed bolt, 44^a, taking through a slot, 44^b, in said cross arm, 44, and into the upper edge or web of the deflector, a cable, 45, being connected at the other end of the stem and extending around suitable guide pulleys and attached to the stem, 46, of the piston, 47, playing in a cylinder, 48, the construction being such as will be understood from the description that the admission of compressed air or other motive fluid into the cylinder, above the piston causing the latter to be depressed forcibly, will operate to draw upon the cable for lifting the deflectors. For adjusting the deflectors to vary the angle at which they extend obliquely across the rails and also the distance to which they extend outside the rails respectively, the slot, 44^b, is formed in the arm, 44, as described, in a curve about the pivot of the wing, and the bolt, 44^a, can be tightened to hold the wing at any position to which it may be adjusted within the range of the curved slot.

When it is desired to operate the device for gathering material from a point beyond the reach of the deflectors, 40, but within the reach of the wing, 1, the outer end of the deflector, 40, is preferably connected to the inner side of the wing, 1, and for that purpose, the deflector is provided at the upper corner of its outer end with a lug, 40^a, and upon the inner side of the wing there is hung a hook, 40^b, adapted to engage an eye in the lug for locking it at a position at which the outer end of the deflector is lodged against a lip or flange, 40^c, which is provided upon the inner side of the wing, 1, to afford such lodgment. For conveniently disposing of the hook, 40^b, when not in use for the purpose indicated, it is swung back to position for engaging with a lug, 40^a, on the inside of the wing. When the deflector is to be employed merely for gathering inside the rails material which lies directly outside, without the necessity of distributing the material lengthwise along the track, it is designed to be mounted at the lowermost position within the range of the curved slot, so that it engages the material less abruptly than when it is at the outermost position, at which it may be latched, as described to the wing, 1. When it is in the latter position, its more abrupt action upon

the material engaged, adapts it for distributing material lengthwise of the track, as well as gathering it inward. When employed for thus gathering material inward for filling in between the rails, and for distributing such material along the track in order to fill in the same evenly though the material engaged may be unevenly distributed originally outside the rails, an excess of material will thus be gathered inward by the wing, 1, and deflector, 40, and such excess after it has been carried across the area comprising the path of the deflector, 40, must in some manner be reconveyed outward across the rail to be deposited outside. For this purpose the two deflectors, 40, are pivoted as shown, spaced apart at their inner ends so as to leave a throat or path between them through which the excess of material may pass; and a short distance in front of this opening there is mounted a double or V-shaped deflector, 50, having its apex facing toward the opening between the deflectors, 40, and its diverging wings extending off outwardly in an opposite direction across the top of the rails. This deflector is pivotally mounted at its apex on the car upon a vertical pivot rod, 51, on which it is adapted to be raised and lowered, the lugs, 50^a, by which it engages the pivot rod, being spaced apart a less distance than the upper and lower supports of the pivot rod. For raising and lowering the deflector, there is connected to its stem, 52, a cable, 53, and 35 tending over guide pulleys, 42, and 55, and thence to the stem of the piston, 47.

The stems, 46 and 52, of the two deflecting devices described, have each a plurality of apertures, 57, and the bearing sleeves of these stems are apertured so that a pin, 58, being inserted through the apertured bearing, and any one of the holes, 57, will secure the device at any position to which it may have been lifted. And when either device has been lifted to the highest point at which it is out of service, the lower edges being above the material which has been placed in its path, the other device may be raised and lowered freely independently of the one which is thus secured out of service; or both devices may be raised to their highest position at the same time or both lowered to the same position, so as to be both in service or both out of service or either one in service, and the other out of service, as the case may require.

For gathering the material thus inward across the rails to the space between the track, the deflectors, 40, preferably at their portion which extends outside the rails, should extend down as near to the ties as possible without incurring danger of collision with them, so as to leave the rails projecting clearly above the ballast or filling material; but at their portion which extends

inward from the rail, the purpose being to fill in material in sufficient quantity to be tamped between and under the ties, the lower edge of the deflectors at the position adjusted for service is in no instance required to be lower than the top of the rails, and usually somewhat higher. But the device is adapted for clearing the space between the rails when desired, by the provision of a plate, 60, mounted on the side of the deflector, 40, at the portion which overhangs the road bed between the rails, such plate being adapted to be adjusted downward so as to project inside the rails to as low a point as may be desired to clear the space above the ties. For securing this plate either in service or out of service, it is provided with slots, 60^a, for fastening bolts, 60^b, the slots having a vertical extent sufficient for the vertical adjustment of the plate from a position in service to a position out of service, and having offsets, 60^c, at the upper and lower ends of such vertical extent in which the bolt stands when it is tightened for holding the plate in position. This construction prevents any danger of the plate slipping from the position to which it is adjusted.

For shaping the side of the road bed when it consists of an embankment, there may be mounted upon the side of the wing, 1, a shaper, 70, extending down past the lower edge of such wing, at the angle at which it is desired to slope the side of the embankment, and this device will serve for finishing the embankment evenly or for evening up an old embankment which may have become eroded by water or for shaping off both the top and sides of such embankment. The simplest form in which such device may be employed, is that in which it is shown in dotted line in Fig. 13, secured by bolts across the outer end of the main portion, 1. It will frequently happen however that an embankment requires finishing up not only on the steep sloping sides but on the surface which is horizontal or slightly sloped away from the ties, and that for such purpose, material will have to be distributed along the side of the track for filling in erosions and supplying other waste, and that such material not being distributed exactly as required, must be redistributed lengthwise of the track in the operation of shaping the bed and depositing the material to fill up irregularities. Now, the angle at which the wing, 1, will be arranged to extend for its ordinary service, is not the most desirable or effective angle for thus distributing material, being not sufficiently divergent from the direction of travel and thereby inadapted to attack the material with sufficient abruptness for distributing lengthwise of the track. A preferable device therefore for this purpose, is

that shown in full lines in Fig. 13, in which a supplemental spreading and distributing wing, 81, is hinged to the outer side of the wing, 1, and adjustable as to the angle thereon, by means of a controlling link, 82, pivoted to the free end of the wing, 81, and provided with a plurality of points of connection on the side of the wing, 1, so that it can be swung flat alongside the wing as shown in dotted line in Fig. 14, or swung out to the most desirable position for the service desired, as shown in full lines. This wing serves to shape the top of the embankment at the proper slope,—or horizontal if the lower edge of the wing is so formed,—and for shaping the side of the bank, the shaper, 70, is bolted across the end of the wing, 81, in the same manner as it might be bolted across the end of the wing, 1, as first above described. When the situation is such as to make it practicable to use the shaper attached directly to the wing, 1, it may be connected only pivotally thereto, and at a single point, its rigidity in operative position being secured by extending it up past the wing, 1, and securing its upper end on the framework of the car. Such a construction is shown in Fig. 15, in which the shaper, 70^a, is thus attached at a single point at 70^b, to the wing, 1, and extends up to a supporting guide bolt, 70^c, on an upright portion of the frame work, and is provided with a long slot, 70^d, which receives said support and guide bolt, 70^c, so that the shaper, 70^a, runs on the latter, in the swinging movement of the wing, 1. I prefer however, instead of providing the bank-shaping devices for attachment to deflecting wing, 1, to mount upon the rear end of the same car with such deflecting wing, and its appurtenances, a complete bank-shaping apparatus which may be used co-operatively with the deflecting apparatus already described, on the forward portion 45 of the car. These independent bank-shaping devices will now be described.

A main spreading wing, A, is pivoted at its forward end in a similar manner to the main wing, 1, above described, and is connected for co-operation with the heel spreader, B, which is also mounted similarly to the heel spreader, 2, above described, a bank-shaper, C, being secured to the outer end of the main wing, A, in a manner similar to the mounting of the shaper, 70, on the wing, 81, above described, the position and path of swinging movement of the entire device being controlled by links connecting the wing, A, with the side of the car in a manner quite similar to the connection and control of the wing, 1, by the links, 17, and 18, above described. The entire device comprising said parts, A, B, and C, is mounted toward the rear end of the car, 35 that is rearward of the scope of action of

the wing, 1, when that wing is operating as a spreader,—that is when the car is moving with the pivoted end of that wing forward. The following is a detail description of these rear bank-shaping devices.

The pivot, D, of the wing, A, (see Fig. 24) is similar in all respects to the pivot, 5, of the wing, 1, and it is secured in the sliding block, E, in the same manner as said pivot, 5, is secured in the post member, 4. 70 The block is mounted for sliding up and down in a short hollow post composed of two facing channel bar members, F, F, similar in construction to the hollow post, 3, 3, the block E, having a plurality of holes, E¹, for receiving a pin, which may be inserted through the web of one of the members F of the hollow post, for securing the block at varying positions, within the desired range of vertical adjustment. The heel member, B, is hinged for swinging horizontally upon a vertical pivot rod, G, which is conveniently mounted upon the rearmost of the hangers, 19, said hanger having lugs, 19^a, at the top and bottom for holding the pivot rod, G, and the heel member, B, having its pivot lugs, B¹, nearer together than the lugs, 19^a, at an amount sufficient to permit the desired range of vertical adjustment of the heel member. The main wing, A, and the heel member, B, are connected for transmission both of the swinging movement and of the up and down movement by a link, B², connected to the heel member near the upper, inner corner and to the wing at the upper edge near the forward end. This connection, it will be observed, causes the raising and lowering of the block, E, carrying the pivot, D, to raise and lower the heel sliding it on its pivot post, and the swinging of the wing, A, vertically up and down edge-wise, also raises and lowers the heel, while the in and out swinging movement of the wing is communicated to the heel. For controlling the swinging movement of the wing, A, it is connected with the car body by links H, pivoted to the wing at different points in the width and to the car body at different points in the height. For bracing the wing most effectively at its lowest operative position, there is provided an additional brace link, H¹, pivoted on the car preferably lower than either of the links, H, and pivoted to the wing near the middle of its width, so that at the lowest position of the wing it 120 stands more nearly the middle of the wing than the links, H, H. For further bracing the rear end of the wing, it may be provided with a link, H², near the middle of the wing and at a higher point on the car than the links, H. All the links H¹, H² and H³, are extensible, comprising two telescoping members, the outer of which has a plurality of holes, H¹⁰, for receiving a pin H¹¹, which engages the interior member of the link. 125

The wing, A, in folding up against the side of the car can be brought closer to the car by offsetting the pivots of the lower links, H, to the car a little farther from the car than the pivots of the upper links, H, are offset, and correspondingly offsetting the pivots of the upper links to the wing, A, farther from said wing than the pivots of the lower links are offset from said wing. This difference in the offsetting of the several pivots may be clearly seen in Fig. 21.

As a matter of convenience, one of the two bolts, C¹, by which the shaper, C, is made rigid with the wing, A, may be removed when the shaper is not to be in service, leaving only the bolt nearest the forward end of the shaper, for connecting it with the wing, and this bolt serves as a pivot about which the shaper may be swung back to position shown in Fig. 22, the link H³ being disconnected from the car and swung over to a position where it may be connected with a lug A¹⁰, on the wing, A, for holding the shaper up out of operative position as seen in said Fig. 22.

The bank shaper, C, is preferably provided with a special brace link, H³, pivoted to the car at a height intermediate the level of the pivots of the links, H, to the car, (though the precise point is a matter of judgment, and may be varied considerably) and to the shaper, C, at a point beyond the end of the wing, A.

For locking the wing, A, either down or up for service or out of service, there is provided a latch bar, J, pivoted at a suitably elevated position on the frame, having a notch, J¹, near its outer end back of the head, J², for engagement with an eye, A³, on the wing, A, at the upper outer corner of the wing, A, the latch bar being of such length from its pivot to the notch, J¹, as to engage the eye when the wing is swung down to operative position; and for adjusting this operative length to vary the height at which the wing is thus locked, the latch bar has a plurality of pivot holes, J³, any one of which may be selected for engagement with its pivot on the frame. The wing is connected with a cable, K, for raising and lowering the wing. Said cable extends over an elevated guide, pulley, K¹, thence down to a pulley, K², on the upper end of the stem K³ of a piston; playing in a cylinder, K⁴, the cable passing from said pulley to a point of fastening on said frame, so that when the piston is forced down in the cylinder by the admission of motive fluid to the cylinder, the wing is lifted. The weight of the wing and connected parts causes it to fall to operative position when released from the upholding means.

For disengaging the latch bar, J, upon the first pull of the cable for lifting the wing, it is pivoted on the wing near the eye,

A⁸, a bell-crank lever, A⁶, having an abutment, A⁹, which engages the latch when the lever is rocked for swinging forward its upstanding arm, and the cable, K, is connected to the wing, A, for lifting it by fastening to the stem of a guide eye, A⁵, through which eye the cable runs, being intermediate its fastened end and said eye looped back through a loop link, A⁷, attached to the said upstanding arm of the bell-crank lever.

For shaping the side of a cut or an embankment higher than the track upon which the car is operating, the wing, A, may be provided with an extension in lieu of the oblique bank-shaper, C, and such attachment is shown on the wing, A, of the left-hand side of the car. It will be understood, however, that either equipment is to be employed upon either side of the car, both sides being equipped alike with either device, or one with one device and the other with another, as the situation may require. The extension piece, M, which may be substituted for the shaper, C, is bolted firmly onto the face of the wing, A, lapping it for sufficient distance to insure rigidity of extension. The wing, A, may be recessed or cut away at the inner end of its lower edge as seen at A⁸, Fig. 17, to afford clearance for the projecting ends of the dies so that the wing may be lowered, as shown in said figure for trimming the road bed to the bottom of the ties and in a slope outward therefrom. Fig. 20 shows the wing with this extension adjusted at the operative position for shaping the side of a cut or higher embankment alongside the track. At this position, the link, H², it will be seen, is substantially horizontal, and the link, H³, is connected to the extension, M, at a point corresponding in its relation to the other pivotal connections to a point on which it is connected to the shaper, C, when that member is inserted, its said connection of the link to the extension, M, being therefore near the lower edge of that member. The links, H² and H³, will be adjusted in length to brace the wing with extension, M, at the position of service, be it higher or lower, and for further bracing and locking the wing when it is operating with the extension, M, there are provided additional brace links, M⁴, and M⁵, for which pivotal connections are provided near the upper and lower outer corners, respectively, of said extension, M, the brace link, M⁴, extending thence upward and forward, and the link, M⁵, extending upward and rearward to elevated pivotal connections on the car. These links are of similar construction to the other links, H² and H³, each comprising telescoping members adapting them for adjustment for bracing the extension, M, at any desired working position.

It will be seen, therefore, that the wing with extension, M, is braced at its outer end by one

link extending upward and forward and by another extending downward and rearward in addition to the bracing afforded by the links which primarily control the swinging 5 movement of the wing.

The structure described comprising the spreading or gathering wing, 1, is designed to be serviceable not merely for distributing and leveling loose material, but also for 10 reducing the banks and marginal area along the track to condition for such distribution and leveling by process of loosening and excavating, and for that purpose the wing, 1, is designed to serve as a plow beam on which 15 plows may be mounted to be carried at any desired distance from the track within the range of the wing for plowing up material which may be subsequently gathered, spread and leveled by the apparatus, or for plowing 20 out and rectifying the lines of the drainage ditch or furrow extending along the side of the track. For this purpose, it is essential that means should be provided for mounting the plow on the wing or plow beam, 1, so 25 that its land side shall be parallel with the direction of travel, and in view of the mounting of the wing for swinging sidewise divergently from the car, this requisite involves a provision for adjusting the plow 30 angularly about a vertical line to compensate for the angular adjustment of the wing. For the accomplishment of these purposes, there is provided a swinging bracket, *a*, adapted to be pivoted at one end to the land 35 side of the plow, and at the other end to the wing and provided with means for securing it in angular adjustment about its pivot to the wing. From the wing there are mounted pivot brackets, *b*, any suitable number of 40 pivot brackets being provided for connecting a plow by means of the swinging bracket, *a*, and at different positions in the length of the wing, and inside or outside, according to whether it is a right-hand or left-hand 45 plow.

The bracket, *a*, is constructed for rigid adjustable connection with the plow by means of a vertical slot, *c*, extending longitudinally of the bracket, which receives 50 a rigid flat stem, *d*, extending upward from the land side of the plow, the bracket having also a downwardly extending arm, *e*, to which at its lower end the plow is pivoted for swinging in a vertical plane. Two bolts, 55 *f*, *f*, are provided for securing the stem, *d*, in the slot, *c*, at a plurality of positions in the range of the vertical pivotal movement of the plow so that by selection of the proper holes, the plow may be adjusted with its 60 lower face horizontal or inclined in either direction with respect to the bracket to compensate for the incline of the wing on which the bracket is mounted, as hereinafter described, so that the plow may stand horizontally. When the plow is right handed and

is mounted on the outer side of the wing or plow beam, 1, the rear end of the swinging bracket, *a*, is pivoted to one of the pivot branches, *b*, and the forward end is connected by a two part extensible link, *g*, *h*, 70 the two members, *g* and *h*, being longitudinally adjusted upon each other and secured with an operative length, such as to offset the plow divergently from the wing at the same angle at which the wing itself is offset divergently from the car; that is to make the land side of the plow parallel with the car or the direction of advance. When the plow is left handed and to be mounted on the inner side of the wing, the forward end 75 of the swinging bracket, *a*, is connected to one of the pivot brackets, *b*, and the rear end is connected by the link, *g*, *h*, to another of said pivot brackets, similar adjustment of the link being made to set the land side 80 of the plow parallel with the track.

When the bar or arm on which the plow is carried is the deflector, 1, as illustrated, said arm or bar may operate not merely as a beam for carrying the plow, but in its full capacity as a deflector, coöperating with the plow in either of the following ways: The plow may be mounted on the forward side of the deflector so as to plow up the earth in advance of the deflector, which the latter, following, either spreads or gathers, according to the direction of travel; or the plow may be mounted on the rear side of the deflector so that the deflector having spread and leveled the earth, the 100 plow, following after, may turn a furrow for a drainage ditch below the leveled surface. The plow also when mounted upon the main deflector, 1, or any arm or bar in that position, coöperates effectively with the 105 bank-shaping devices mounted upon the rear end. Thus, the plow may be set to turn the furrow along the line at which the embankment forming the road bed is to be trimmed by the bank-shaper when the earth 110 it too firm or solid, or the embankment too uneven to be readily trimmed by the shaper attacking it without the preparatory work which may be done by the plow.

I claim:

1. A railway grader comprising in combination with a car, a wing connected to the side of the car for swinging about one end vertically edgewise and also sidewise; a means for such connection comprising a plurality of pairs of links, said pairs being at a substantial distance apart along the length of the wing, two links of each pair being at their pivots to the wing spaced apart in the width of the wing and at their pivots to the 120 car similarly spaced apart in the height of the car.

2. A railway grader comprising in combination with a car, a wing pivoted at one end of the side of the car for swinging ver- 125

- tically sidewise and also for swinging divergently from the side of the car; two pairs of links which connect the wing to the side of the car, said links being pivoted both to the wing and to the car for remaining connected both to the wing and the car throughout the swinging movement of the wing, said links being at relatively wide distances apart on the wing and at approximately like distances apart on the car, and being both situated remotely from the pivoted end of the wing, the said links having their respective pivots on the car and wing distributed along the length of the car and wing and graduated in length according to their position in the length of the wing, each pair comprising an upper and a lower link, the upper links of said pairs having their pivotal connections with the car at a level intermediate the levels of their connections with the wing at the operative and inoperative positions, respectively, of the wing.
3. A railway grader comprising, in combination with a car, a wing connected to the side of the car for swinging about one end vertically edgewise and also sidewise divergently from the car, the means for connecting the wing to the car during its swinging movement comprising an upper and a lower set of links, each set consisting of a plurality of links which extend between the side of the car and the wing and are pivotally connected to both the parts between which they thus extend, each set of links being distributed at their connections to the wing along the length of the wing, and at their connections to the car along the length of the car, and being graduated in length according to their position in the length of the wing.
4. A railway grader comprising, in combination with a car, a wing pivoted at one end at the side of the car for swinging up and down, and also for swinging divergently from the car, an upper and a lower set of links connecting the wing to the car during its swinging movement, the pivotal connections of the two sets being positioned substantially in parallel lines on the wing, and also in parallel lines on the car.
5. A railway grader comprising, in combination with a car, a wing pivoted at one end at the side of the car for swinging up and down, and also for swinging divergently from the car; an upper and a lower set of links connecting the wing to the car, the pivotal connections of the two sets being positioned substantially in parallel lines on the wing, and also in parallel lines on the car; the pivotal connections being adapted to accommodate fore and aft movement of the links.
6. A railway grader comprising, in combination with a car, a wing pivotally connected at one end to the side of the car for swinging up and down and also for swinging divergently off from the car; an upper set and a lower set of links connecting it with the car, the pivots to the car of the links of the lower set being offset farther on the car than those of the upper set, and the pivots to the wing of the links of the upper set being offset farther from the wing than those of the lower set.
7. A railway grader comprising, in combination with a car, a wing pivoted at one end at the side of the car for swinging up and down and also for swinging divergently from the car; a plurality of upper links of graduated length distributed along the length of the wing connecting it to the car, and a plurality of lower links of graduated length distributed along the length of the wing for connecting it at a lower point with the car; the two sets of links at the operative position of the wing being in substantially parallel planes.
8. A railway grader comprising, in combination with a car, a wing pivoted at one end at the side of the car for swinging up and down and also for swinging divergently from the car; two sets of links in different planes connecting the wing with the car, the links of each set being graduated in length according to their distance from the pivoted end, their pivotal connections with the wing being in two substantially parallel lines and their connections with the car being also in two substantially parallel lines, the distances between the parallel pivot lines on the wing and on the car being substantially equal.
9. In a railway grader in combination with a car, a wing connected to the side of the car for swinging about one end vertically edgewise and also sidewise divergently from the car; links which connect said wing to the car distributed along the length of the wing and graduated in length to affect the divergence of the wing; a latch and bracing bar pivoted at an elevated forward position on the car extending thence rearward; a device situated toward the rear end of the wing with respect to which said latch bar slides longitudinally in the swinging movement of the wing; the latch bar having means for engaging said device to limit the movement of the wing; lifting means connected to the wing and extending to an elevated point on the car for raising and lowering the wing; a latch-releasing device for disengaging the latch bar, and connections from the latch-releasing device to the wing-lifting means for releasing the latch by the lifting action.
10. In a railway grader in combination with a car, a wing connected to the side of the car for swinging about one end vertically edgewise and also sidewise divergently from the car; links which connect said wing to the car distributed along the length of the

- wing and graduated in length to affect the divergence of the wing; a latch and bracing bar pivoted at an elevated forward position on the car extending thence rearward; a device situated toward the rear end of the wing with respect to which said latch bar slides longitudinally in the swinging movement of the wing; the latch bar having means for engaging said device to limit the movement of the wing and the sliding latch bar; a cable connected to the wing, and a guide at an elevated position over which the cable extends for lifting the wing; a latch-releasing device on the wing for disengaging the latch bar therefrom, comprising a pull rod; said pull rod having an eye through which the lifting cable extends near the attachment of the cable to the wing and out of line with the direction of the pull of the cable in lifting; whereby the lifting action of the pull rod uplifts the latch for releasing the bar.
11. In a railway grader, in combination with a car, a post fixed at the side thereof; a bracket mounted at the side of the post; the bracket and post being provided with coöperating means for securing the bracket to the post at a multiplicity of positions in the range of the sliding movement; a vertical pivot bolt mounted on the post; a heel spreader pivotally mounted for sliding on said vertical pivot; a main spreading wing pivoted to the sliding bracket for swinging vertically edgewise, and also for swinging toward and from the car; means connecting the wing with the heel spreader for raising and lowering the latter in the up and down movement of the wing, and for transmitting from one to the other movement toward and from the car.
12. In a railway grader, in combination with a car, a spreading wing pivoted to the car; means for swinging it up and down and in and out about its pivot; a heel spreader and a vertical pivot mounted on the car forward of the pivot of the wing; the heel spreader being mounted for sliding on and swinging about such vertical pivot; means connecting the wing with the heel spreader for raising and lowering the latter in the up-and-down swinging movement of the wing, and for transmitting lateral swinging movement from one to the other.
13. In a railway grader in combination with a car, a spreading and leveling device comprising a heel piece and a main spreading wing, the heel piece being connected to the side of the car on an extended vertical pivot on which it is movable up and down, the main spreading wing being pivoted to the side of the car independently of the heel piece for swinging toward and from the car, said wing being pivoted also for swinging vertically edgewise, and means by which the vertical sliding movement of the heel piece is derived from the vertical swinging movement of the wing.
14. In a railway grader, in combination with a car, a spreading and leveling device comprising a heel piece and a main spreader, the main spreader being pivoted at its forward end to the side of the car for swinging up and down and also for swinging toward and from the car, and means connecting it with the car for controlling its said movements and maintaining it substantially vertical throughout such movements, the heel piece being connected to the side of the car on an extended vertical pivot on which it is vertically movable, and connections between the heel spreader and the main spreader for transmitting to the former the up-and-down movement and the lateral movement of said main spreader.
15. In a railway grader, in combination with a car, a wing mounted upon the side of the car, extending obliquely off therefrom to engage material outside the rail, and a gatherer mounted under the car extending obliquely outward across the rail and terminating between said outside wing and the rail.
16. In a railway grader, in combination with a car, a deflector hinged at one end to the side of the car, means for adjusting and securing it at a position extending obliquely off from the car, a supplemental deflector, a support to which it is pivoted at one end under the car, and means by which it is secured extending obliquely in the same general direction as the outside deflector with its outer end proximate to the inner side of the outer deflector.
17. In a railway grader, in combination with a car, a deflector hinged at one end to the side of the car; means for adjusting and securing it at a position extending off obliquely from the car; a supplemental deflector positioned underneath the car adapted to extend in the same general direction as said outside deflector and hinged at the same end for swinging laterally to vary its obliquity, and means for securing it at oblique position with its outer end contiguous with its inner side of the outer deflector.
18. In a railway grader, in combination with a car, a deflector hinged at one end to the side of the car, means for adjusting and securing it at a position extending obliquely off from the car for gathering material inward from outside the rail when the car travels with the free end of the wing foremost; a supplemental gathering deflector mounted underneath the car and extending across the rail into the space between the outside deflector and the rail for deflecting into the space between the rails, material which is gathered toward the rail by the outside deflector, and a spreader

under the car extending across the same rail in the oppositely oblique direction from that of said inside gathering deflector, said spreader having its inner end extending 5 past the inner end of the said inside gathering deflector.

19. In a railway grader, in combination with a car, a gatherer and a spreader positioned under the car above the area of the 10 track between the rails extending obliquely in opposite directions outward across one rail, the gatherer having its inner end positioned nearer said rail than the inner end of the spreader, and an outside gatherer 15 hinged to the side of the car intermediate the outer ends of the gatherer and spreader, and extending in the same direction as the gatherer obliquely off from the car for gathering material inward toward the rail 20 into the path of the first mentioned gatherer.

20. In a railway grader, in combination with a car, a gatherer and a spreader positioned under the car above the area of the 25 track between the rails extending obliquely in opposite directions outward across one rail, the gatherer having its inner end positioned nearer the rail than the inner end of the spreader; an outside gatherer hinged to the side of the car intermediate the outer 30 ends of the gatherer and spreader, and extending in the same direction as the gatherer obliquely off from the car for gathering material inward toward the rail into the path of the first mentioned gatherer, and 35 means for adjusting and securing the first mentioned gatherer with its outer end contiguous to the outside gatherer.

21. In a railway grader, in combination with a car, a deflector connected to the side 40 of the car and extending off obliquely therefrom for engaging material outside the track, the lower edge of such deflector being recessed or cut back for a distance from its inner end, and a plate mounted on the 45 deflector and adjustable up and down to uncover and cover such recess.

22. In a railway grader, in combination with a car, a deflector connected to the side of the car and extending off obliquely therefrom for engaging material outside the 50 track, the lower edge of such deflector being recessed or cut back for a distance from its inner end, and a plate mounted on the deflector and adjustable up and down to 55 uncover and cover such recess, such plate having for securing it in such adjustment vertically-extending bolt-slots having horizontal offsets at their upper and lower ends, and bolts taking through such slots 60 for clamping the plate to the deflector, the upper and lower offsets being positioned for entrance of the bolts thereto at the lower and upper positions respectively of the plate.

65 23. In a railway grader, in combination

with a car, a gathering deflector and a spreading deflector, both mounted underneath the car and extending obliquely off toward the same side and across the same rail; vertical stems to which said deflectors, 70 respectively, are connected for up-and-down movement; cables connected to said stems respectively; elevated pulleys over which the cables extend; means connected with the cables for operating them to raise and lower the deflectors, the deflector stems having each a plurality of apertures and pins for insertion in said apertures above the guide bearings of said stems for securing the deflectors at any position to which they 75 may be elevated.

24. In a railway grader, in combination with a car, a deflector pivoted at one end to the side of the car for swinging up and down and also for swinging toward 80 and from the car, the pivotal connection for such swinging movements being a T whose stem is horizontal and whose cross is transverse to the length of the deflector, the deflector being pivoted on the cross bar of the 85 T; a bearing on the car in which the stem is journaled, the stem having an annular groove and the bearing having a key pocket extending transversely to the seat of the stem in such bearing, and a key in such 90 pocket engaging the annular groove of the stem.

25. In a railway grader, in combination with a car, a spreading wing pivotally connected at its forward end to the side of the 100 car for swinging edgewise vertically, and also for swinging toward and from the car; two links by which it is connected to the car, said links being pivoted to the wing remotely along its length from the pivoted 105 end of the wing, and to the car remotely along its length from the wing pivot, the connections of said links to the wing being widely separated in the width of the wing, and their connections to the car being widely 110 separated vertically on the car, for controlling the swinging movement of the wing about its pivot, and brace links extending from the car at points thereon remotely rearward from the wing pivot to the rear portion of the wing, said brace links being 115 positioned and proportioned for bracing the wing off from the car at a position at which it extends operatively upward, rearward and outward.

26. In a railway grader, in combination with a spreading wing pivotally connected at its forward end to the side of the car, two links by which it is connected to the car in addition to its said pivotal connection at the forward end, said links being pivoted to the wing at separated points in the width of the wing remote from the pivoted end, and to the car at points vertically separated in the height of the car remote from the 120 125 130

- wing pivot, for controlling the swinging movement of the wing about its said pivot to the car, and two brace links in addition to those which are concerned in the swinging movement of the wing extending from the car to the rear portion of the wing, positioned and proportioned for bracing the wing off from the car at a position at which it extends obliquely upward, rearward and outward, one of said links being extended from an elevated point on the car downward and outward for connection with the rear end portion of the deflector, and a hanger depending from the car frame for affording a pivotal connection from which the other of said brace links extends upward and outward to the wing.
27. In a railway grader, in combination with a car, a wing pivoted at its forward end to the car for swinging up and down, and also for swinging off sidewise divergently from the car; links which remain connected at their opposite ends respectively to the wing and the car for permitting and controlling the path of such swinging movement, both up and down and divergently, and two brace links in addition to those which are concerned in said control of the swinging movement, said brace links being extended from the rear end portion of the wing, one upwardly, inwardly and rearwardly, and the other downwardly, inwardly and rearwardly to the car.
28. In a railway grader, in combination with a car, a road-bed-shaping device comprising a heel spreader hinged to the car for swinging horizontally and movable upward and downward at its said hinged connection; a wing hinged to the car for swinging horizontally and also for swinging up and down, and a link connecting the heel spreader with such deflector at a point on the latter located outward from the pivot of the edgewise movement of the latter.
29. In a railway grader, in combination with a car, gatherers mounted overhanging the track area between the rails and together approximately spanning the entire width of said area under the car, diverging from their ends intermediate the rails obliquely outward and extending across the opposite rails, respectively; rods on which such gatherers, respectively, are pivoted at their inner ends for swinging independently of each other, to vary independently their angles of obliquity to the rails; a bar extending above the paths of swinging movement of said deflectors, said bar having a vertical stem mounted upon the car and adapted for vertical adjustment thereon; means for raising and lowering said stem and securing it at a plurality of positions within its range of vertical movement, and means for securing the deflectors, respectively, to the bar at a plurality of positions within the range of their respective swinging movements under the same.
30. In a railway grader, in combination with a car, a gatherer hinged underneath the car for swinging horizontally, means for adjusting and securing it at a position at which it extends obliquely outward across one rail for gathering material from outside the rail to the space between the rails; such gatherer having its lower edge at the part which is inside the rail higher than the part of said edge which is beyond the rail by substantially the amount of the height of the rail; a plate mounted on the side of the gatherer inside the rail and adjustable up and down, and means for securing it at a position extending below the lower edge of the gatherer and also at a position at which it does not protrude below said edge.
- In testimony whereof, I have hereunto set my hand at Chicago, Illinois, this 4th day of April, 1910.

ORVILLE C. MANN.
